CUP HOLDING ATTACHMENT FOR CHAIR ARM ASHTRAYS OR THE LIKE

Jerry R. Anderson, 6252 Bion St., San Gabriel, Calif., and Tom T. Ishii, P.O. Box 533, El Monte, Calif.

Filed May 20, 1963, Ser. No. 74,944

Term of patent 14 years

(Cl. D44—10)

FIG. 1

FIG. 2

FIG.4

FIG. 1 is a perspective view of a cup holding attachment for chair arm ashtrays showing our new design;

FIG. 2 is a slightly smaller scale top plan view;

FIG. 3 is a bottom plan view;

FIG. 4 is a side elevational view; and

FIG. 5 is an end elevational view.

We claim:

The ornamental design for a cup holding attachment for chair arm ashtrays or the like, substantially as shown.
